UNITED STATES PATENT OFFICE.

FRANK H. GROVE, OF COLUMBIANA, OHIO.

ANNULEAR SHUTTLE.

Application filed May 14, 1923. Serial No. 338,901.

To all whom it may concern:

Be it known that I, FRANK H. GROVE, a citizen of the United States, residing at Columbiana, in the county of Columbiana 5 and State of Ohio, have invented certain new and useful Improvements in Annular Shuttles, of which the following is a specification.

This invention relates to improvements in 10 annular shuttles such as are used upon the class of machines designed to spirally wrap a narrow strip of paper or the like around an annulus, such as a tire casing, and has for its objects to improve the mechanism 15 upon the shuttle including the folder device which folds the edge of the paper, and to provide an adjustable guide roller which guides the folded paper from the folder device to the annulus to be wrapped.

20 As is well known, the tire casings are wrapped with strips of paper before being shipped from the factory, the strips of paper being usually spirally wound around the casing. In my copending application Serial 25 No. 543,445, filed March 13, 1922, is illustrated a wrapping machine to which such a rotary shuttle is applicable.

The objects of the invention may be attained by constructing the shuttle as illustrated in the accompanying drawings, in 30 which—

Figure 1 is a front elevation of a shuttle embodying the invention, showing the same in the operative position, a tire casing being shown in cross section therein;

Fig. 2, an edge elevation of the same;

Fig. 3, an enlarged elevation of the folder device;

Fig. 4, a section on the line 4—4, Fig. 3;

40 Fig. 5, a section on the line 5—5, Fig. 1; and

Fig. 6, an end elevation of the feed roll.

Similar numerals refer to similar parts throughout the drawings.

45 The annular shuttle is indicated generally at 1 and is provided with a gate 2 hinged as at 3 in one side of the gap 4 formed in the shuttle and provided with a latch 5 at its swinging end, for normally holding the gate in closed position to form a continuous annulus.

55 A pin 6 is carried by the latch bar and arranged to be grasped in the hand of the operator together with the pin 7, which is fixed in the gate, for the purpose of easily

unlocking the latch bar when it is desired to open the gate.

The paper tape 8 which is used to wrap around the tire 9 or other annulus, is carried in a stock roll 10 which is wound upon 60 a spool 11 which is journaled upon the spindle 12 carried by the shuttle.

The paper tape as it passes from the spool, is carried over a pin 13 and into the paper folder which includes the casting 14 connected to the shuttle by the bolts 15 which also serve to attach the plate 16 to the outer end of the casting.

A pair of conical rollers 17 and 18 are journaled upon the plate as at 19 and 20 70 respectively, said rollers being preferably mounted upon centers diagonal to the median line of the plate as shown. The roller 17 is provided with a peripheral flange 21 and the roller 18 has a similar flange 22 75 preferably of greater thickness than the flange 21.

The folder plate 23 is connected to the upper portion of the casting 14 and provided with the tapered edge 24 which extends between the rollers 17 and 18, the tapered under edge 25 thereof being located in proximity to the conical portion of the roller 18.

The paper tape 8 is carried over the folder 85 plate 23, one edge thereof being extended between the rollers 17 and 18 and carried under the inclined edge of the plate as shown at 26, folding this edge of the paper upon itself.

90 As the folded paper tape emerges from the paper folder, it passes over the guide roll 27 and thence to the tire or other annulus to be wrapped. The guide roll 27 is journaled upon a spindle 28, the lower end of which is provided with a head 29, pivoted upon the pin 30 which is carried by the lug 31 provided with a threaded shank 32 which extends through the shuttle, a nut 33 attaching the same to the shuttle.

100 A pair of oppositely disposed arms 34 are fixed upon the head 29 of the spindle and are engaged by the adjusting screws 35 which are threaded through the side face of the shuttle 2 and provided with jamb nuts 36 105 for holding the adjusting screws in position.

The outer end of the spindle 28 may be provided with the reduced, threaded shank 37 upon which the jamb nuts 38 are mounted, these jamb nuts being preferably cir- 110

cular and located within the socket 39 formed in the end of the roller 27.

This spindle may thus be adjusted to hold the roller at any desired angle necessary in order to properly guide the paper tape to the tire, permitting different sizes of tires to be easily wrapped and also permitting the spiral windings of the paper tape to be placed in any desired spaced relation, without causing the paper tape to buckle or wrinkle, as the spindle of the guide roller may be adjusted to the proper angle to prop-

erly feed the paper tape to the annulus to be wrapped therewith.

I claim:—

An annular shuttle having a stock roll of wrapping material, a guide roll over which the wrapping material is passed, a pivoted shaft upon which the guide roll is mounted, an arm extending from each side of the shaft and adjusting screws for engagement with said arm to hold the roll in any desired angular adjustment.

FRANK H. GROVE.
